ELECTROMAGNETIC RELAY OR SIMILAR ARTICLE

Louis C. Beggs, Attleboro, Mass., assignor to Metals & Controls Corporation, Attleboro, Mass., a corporation of Massachusetts

Application March 5, 1957, Serial No. 45,122

Term of patent 14 years

(Cl. D26—13)

Fig. 1.

Fig. 2.

Fig. 1 is a top perspective view of an electromagnetic relay or similar article, showing my new design; and

Fig. 2 is a bottom perspective view thereof.

The dominant features of my design reside in the portions shown in full lines in the drawing.

I claim:

The ornamental design for an electromagnetic relay or similar article, substantially as shown and described.
